[57] **CLAIM**

I claim the ornamental design for a combination toothbrush and bottle holder, as shown and described.

DESCRIPTION

FIG. 1 is a perspective view for a toothbrush holder showing my new design thereof;

FIG. 2 is a front elevational view thereof with the rear elevational view being a mirror image;

FIG. 3 is a right side elevational view thereof;

FIG. 4 is a left side elevational view thereof;

FIG. 5 is a top plan view thereof; and,

FIG. 6 is a bottom view thereof.
